UNITED STATES PATENT OFFICE.

JAMES F. PLACE, OF MONTCLAIR, NEW JERSEY, AND ERNEST D. TERRY,
OF BROOKLYN, NEW YORK.

DESIGN FOR A BICYCLE-LAMP.

SPECIFICATION forming part of Design No. 25,440, dated April 28, 1896.

Application filed October 4, 1895. Serial No. 584,673. Term of patent 7 years.

To all whom it may concern:

Be it known that we, JAMES F. PLACE, residing at Montclair, Essex county, New Jersey, and ERNEST D. TERRY, residing at Brooklyn, Kings county, New York, citizens of the United States, have invented and produced a new and original Design for a Bicycle-Lamp, of which the following is a specification, referred to the accompanying drawings, forming a part thereof.

Figure 1 is a side elevation of a bicycle-lamp, showing our design; and Fig. 2 is a plan view of the same.

The leading features of our design consist in the general configuration and ornamentation of the lamp, substantially as herein described.

The body 1 of the lamp is in the form of an upright cylinder having a top part 2, which is of substantially the same diameter as the lower part. This top part 2 has on it and extending around it two ornamental rounded beads 7 and 7'. Just above the lower bead 7' is a band of ornamental open-work 9', and above the upper bead 7 is a band of ornamental open-work 9, composed of rows of apertures. On the circular top of the body, Figs. 1 and 2, is an ornamental raised bead 23, of circular form, inclosing an ornamental open-work 22. Below the bead 7' and separated from it by a plain band is an ornamental rounded bead 8 on and extending around the body, and next below this bead 8

is an ornamental band of open-work 10 in the body. Near the lower part of the body and extending around the same is an ornamental rounded bead 8'.

4 is the oil-fount, and 5 is the gallery-ring. This ring has a broad plain band, and on its lower edge are projections 6, which extend down to the fount 4. The fount 4 has a broad plain band at its lower part and an ornamental molding 4' at its upper edge.

The ornamentation on the side of the body 1 is shown in Fig. 1. Between the beads 8 and 8' and extending transversely across the body are two ornamental parallel bands 12 and 12', and between these bands is an oblong frame 11' with a concave curved contour at its left-hand end, as seen in Fig. 1. In this frame is a circular frame 11", within which is a circular lens 11, convex on its outer face.

We claim—

The design for a bicycle-lamp herein shown and described.

In testimony that we claim the foregoing as our invention we have signed our names, in presence of two witnesses, this 30th day of September, 1895.

JAMES F. PLACE.
ERNEST D. TERRY.
